(21) Appl. No.: 29/471,776

(57) CLAIM

The ornamental design for the wig bag, as shown and described.

(22) Filed: Nov. 5, 2013

DESCRIPTION

(51) LOC (10) Cl. 03-01

FIG. 1 is a perspective view of a wig bag, showing my new design;

(52) U.S. Cl. D3/232

FIG. 2 is a side view thereof;

(58) Field of Classification Search

USPC D3/232, 233, 240–246

USPC D3/232, 233, 240–246

CPC A45C 1/024; A45C 3/06

FIG. 3 is side view opposite that shown in FIG. 2;

See application file for complete search history.

FIG. 4 is a side view thereof of the wig bag in use;

FIG. 5 is side view opposite that shown in FIG. 4;

FIG. 6 is a top plan view of the wig bag; and,

FIG. 7 is a bottom plan view opposite that shown in FIG. 6.

The broken lines showing a portion of the bag are for the purposes of illustrating environment and form no part of the claimed design.
